DOOR CHECK

Edward Frank, Berkeley, Calif.

Application July 18, 1938, Serial No. 219,738

1 Claim. (Cl. 292—288)

This invention relates to devices for use with doors or the like for releasably maintaining the latter in various open positions.

It is an object of the invention to provide a simple and low-cost door check.

Another object of the invention is to provide a device of the character described which may be quickly and easily mounted on and removed from the door.

10 The invention possesses other objects and features of advantage some of which, together with the foregoing, will be specifically set forth in the detailed description of the invention hereunto annexed. It is to be understood that the invention is not to be limited to the specific form thereof herein shown and described as various other forms thereof may be employed within the scope of the appended claim.

Referring to the drawing:

20 Figure 1 is a perspective view illustrating a portion of a door structure and showing the door check of my invention mounted thereon.

Figure 2 is a top plan view of the door check alone.

25 Figure 3 is a front elevational view of the structure shown in Figure 2.

In detail, the door check of my invention comprises a preferably U-shaped member composed of rubber or other similar elastic substance having 30 a pair of spaced legs 4 joined together at one end by an integral arcuate bridge 6. The inner confronting faces 7 of the legs 4 are normally disposed in angular relation so that the legs, at their distal ends, are substantially in contact with each 35 other, and a portion of each leg is cut away so as to provide, at one side of the door check, a V-shaped notch formed by the inclined surfaces 8 which border the leg faces 7.

It is intended that the check shall be mounted 40 on a door 9 between the bottom edge 11 thereof and the surface of the floor 12. This is done by placing the check on the floor with the legs 4 pointing upwardly and with the notch formed by the angular surfaces 8 contacting the vertical 45 edges of the door. Manual pressure is then applied to push the bridge portion 6 of the check horizontally into the gap between the bottom of the door and the surface of the floor. As the check is moved, the edges 13 of the door will ride 50 along the inclined surfaces 8 thereby forcing the

legs 4 apart and flexing the bridge 6 so that when the check is brought to rest in its ultimate position, the surfaces 7 of the legs will be firmly pressed against the front and rear surfaces of the door. If the gap between the door and floor 5 is wider than usual and it is found that after the check has been mounted the latter does not contact the floor, downward pressure may be applied to the upper ends of the legs to shift the check downwardly until the desired contact is 10 obtained.

The door check of my invention just described is obviously quite simple both in construction and in its method of application, may be easily attached to and removed from various doors about 15 the house, may be satisfactorily applied by the ordinary unskilled housewife, and will not scratch or otherwise mar the surface of the floor.

Besides functioning to hold doors in various open positions, the check may be applied also 20 to the vertical edge of the door where it will serve as a bumper to prevent the door from slamming shut. This is particularly useful in connection with doors equipped with glass panels as it has been known that the severe shock imposed on the 25 panel by suddenly slamming a door of this character is often sufficient to crack or shatter the glass. The check is also useful to prevent annoying rattling of doors whose latch bolts have become worn. By placing a check on the door 30 as shown in Figure 1 and closing the door, the slight movement of the latter allowed by the loose or worn latch will be prevented.

Having thus described my invention, what I claim as new and desire to secure by Letters Patent is:

A device of the character described comprising a substantially U-shaped resilient member having a pair of spaced legs and an integral flexible bridge portion joining said legs together at one 40 end thereof, said legs in their normal unflexed positions being in close proximity at the other ends thereof opposite said bridge portion, each of said legs having a surface portion thereof confronting the other of the legs angularly inclined 45 to provide in a side of said U-shaped member a depression of V-shaped cross-sectional form, and said depression extending substantially the entire length of said legs.

EDWARD FRANK. 50
